FIG. 6.

INVENTOR

William C. Coryell
by Thomas H. Ferguson Atty.

UNITED STATES PATENT OFFICE.

WILLIAM C. CORYELL, OF YOUNGSTOWN, OHIO.

SASH.

Application filed March 19, 1921. Serial No. 453,685.

The present invention relates to sash for use in windows, skylights and the like. The principal object of the invention is to produce a marketable sash of great stiffness and durability which can be easily and economically manufactured. In its preferred form my invention contemplates a sash composed of metal parts, preferably rolled shapes such as may be easily produced in a rolling mill. The various features and advantages of my invention will be best understood upon reference to the following detailed description taken in connection with the accompanying drawing, and the scope of the invention will be particularly pointed out in the appended claims.

Fig. 1 is an elevation of a sash constructed in accordance with the present invention, the same being viewed from the outside; Fig. 2 is a similar view of the same sash viewed from the inside; Fig. 3 is an enlarged elevation of one of the joints between the bars of the sash, viewed from the inside; Fig. 4 is a sectional view of the same taken on a plane indicated by the line 4—4 of Fig. 3; Fig. 5 is a view similar to Fig. 3, the parts being viewed from the outside; Fig. 6 is a sectional view of the same taken on a plane indicated by the line 6—6 of Fig. 5; and Fig. 7 is a sectional view similar to Fig. 4 illustrating the parts with a joint in the glass directly behind one of the bars. Throughout these views like characters refer to like parts.

Referring to the drawing in detail, the frame of the sash is made up of stiles 10 and rails 11 which are secured together at their corners in any preferred way. In the preferred form of the invention these stiles and rails are composed of metal and are welded at the corners. Bars 12 and 13 extend between the stiles and rails, respectively, to complete the sash structure. The bars 12 constitute one set and divide the space within the sash frame into long panels or spaces extending from one side of the sash to the other. The bars 13 constitute a second set and divide the whole space in the same way but the long panels lie at right angles to those provided by bars 12, due to the fact that the bars 12 and 13 extend cross-wise of each other. The several

bars are secured to the stiles and rails in any preferred way and their number may be varied to furnish the subdivision of the whole space, which has been decided upon.

The bars 12 and 13 may also be variously shaped. A slight modification of many different forms of angle-bars will suffice to produce bars which will perform the required functions. Thus in forming my bars, I may use as basis, H-bars, I-bars, L-bars, T-bars, Z-bars, channel bars, etc. In view of this fact it will be understood that the T-bars herein disclosed are therefore merely illustrative.

As clearly shown, each of the bars 12 and 13 is composed of two constituent members, one called the flange and the other the web. In the finished structure, the flanges of the bars 12 are secured to the flanges of the bars 13 and the webs extend outwardly. Since in other forms of angle-bars, the webs may be secured together and the flanges extend outward, I have chosen to call those members which are secured together "main" members and those members which extend outward "auxiliary" members.

In the form of the invention chosen for illustration, each bar 13 is provided with two sets of longitudinally aligned ribs 14 which extend from that face of the main member which is farthest from the auxiliary member. These ribs 14 extend only between the bars 12. In other words, if the bar 13 is rolled so as to provide continuous ribs 14, then those ribs are cut away at the points where the bars 13 cross the bars 12. The ribs 14 are of equal height and may closely approach the glass 15 as shown in Figs. 4 and 6, or they may bear permanently against the glass as shown in Fig. 7. In either case the ribs bear against and support the glass when it is subjected to heavy wind pressure which will of course be exerted mainly from the outside. In the former case the supporting action does not take place until the glass is deflected far enough to engage the ribs. In the latter case it takes place without waiting for the glass to be deflected. The latter is the preferable construction for it is desirable to support the glass as much as possible.

The bars 12, which as before indicated are also shown as T-bars, have small ribs 16 on

opposite sides of their auxiliary members. The space between each rib 16 and the adjacent face of the main member constitutes a groove or receiving space for the edge of the glass and the putty or other retaining material 17.

The main members of the bars 12 and 13 bear directly against each other in the finished structure and they may be secured together in any suitable way. In the preferred construction these bars are preferably welded together. Of course other means for securing them may be employed if desired. As previously noted, the auxiliary members of the bars 12 extend outwardly and form ledges for the support of the glass 15. The latter is preferably provided in the form of strips which extend from stile to stile and occupy the spaces between the ledges. These strips of glass 15 are made of such a width that they may be easily passed over the ribs 16 into their final positions in the grooves formed between the ribs and the adjacent faces of the bars 12. In this position the glass may be brought to bear directly against the adjacent faces of the bars 12 and the outer surfaces of the ribs 14 on the bars 13; or, they may be brought into close proximity to these parts, as previously noted. The glass is held in place by putty or other retaining material 17 as before noted.

In case it is desired to use short lengths of glass instead of strips running from stile to stile, the same may be jointed so as to bring the joints in line with the bars 13, as clearly illustrated in Fig. 7. In such event the joint should be brought at some point between the ribs 14 so as to enable the putty or other like material 18 which lies between the ribs and against the glass, to properly close the joint. In the case illustrated, the joint lies directly behind the center of the bar 13. Obviously this is not necessary, although giving the parts a better appearance from the outside. It will be noted that in this instance the ribs 14 bear directly against the glass. Obviously, a satisfactory joint could be made even though the fit was loose at this point, as in Figs. 4 and 6.

From this description it will be seen that I have produced a sash which has great stiffness against wind pressure because so little of the bars is cut away, and at the same time I have produced a structure which can be cheaply and readily manufactured. The latter advantage is contributed to by the fact that so little cutting needs to be done upon the bars.

It will be apparent that in carrying out my invention, many alterations and modifications may be made in the specific structure disclosed without departing from the spirit and scope of my invention. Thus, the bars of the sash may be variously shaped as

I have heretofore pointed out. These and other changes will readily suggest themselves to persons skilled in this art. I therefore do not wish to be limited to the specific structure herein disclosed but aim to cover all such alterations and modifications by the terms of the appended claims.

What I claim as new and desire to secure by Letters Patent of the United States, is:

1. A unitary metal angle-bar comprising main and auxiliary longitudinally continuous constituent members, said members in right section meeting at an angle, said main member having a plane face on its side farthest from the auxiliary member and ribs of equal height extending from said face in two parallel longitudinal rows located near the outer limits of said face, the ribs in each row being spaced apart and each rib being opposite a companion rib in the other row, said companion ribs forming with said face aligned channels along the angle-bar, and all right sections of the angle-bar exclusive of said ribs being identical in area and outline.

2. A unitary metal angle-bar comprising main and auxiliary longitudinally continuous constituent members, the auxiliary member joining along one edge with the main member at an intermediate point in the latter's width, said members in right section thus meeting at an angle, said main member having portions of its surface on its side farthest from the auxiliary member lying on a plane and having parallel longitudinal ribs forming with said plane portions channels along said angle-bar, all right sections of the angle-bar including said ribs being identical in area and outline.

3. In a sash, two sets of angle-bars, each angle-bar comprising a main member and an auxiliary member, said members meeting each other at an angle, the sets of angle-bars crossing each other and the main members of both sets engaging each other and being secured together at crossing points, the auxiliary members of one set of angle-bars forming supporting ledges for the glass, and the main members of the other set having ribs projecting toward the glass between the angle-bars of the first set.

4. In a sash, two sets of angle-bars, each angle-bar comprising a main member and an auxiliary member, said members meeting each other at an angle, the sets of angle-bars crossing each other and the main members of both sets engaging each other and being secured together at crossing points, the auxiliary members of the one set of angle-bars forming supporting ledges for the glass, said auxiliary members having glass-retaining grooves on both sides of each member, and the main members of the other set of angle-bars having a plurality of rows of ribs of

equal height extending toward the glass between the angle-bars of the first set.

5. In a sash, glass-supporting bars, glass positioned on said bars in a plane intersecting said bars, other bars secured to said first mentioned bars at engaging points and lying wholly on one side of said plane, said other bars having each a main portion spaced from said plane and projecting ribs extending toward said plane, said ribs forming on each said bar a channel next to the glass, and retaining material in said channels.

6. In a sash, sets of crossed parallel bars, glass positioned between bars of one set and having a joint opposite one of the bars of the other set, projecting ribs extending from said latter bar toward the glass on opposite sides of said joint, said ribs and bar forming a channel along the joint, and retaining material in said channel.

15
20
In testimony whereof, I hereunto subscribe my name this 17th day of March, 1921.

WILLIAM C. CORYELL.
